UNITED STATES PATENT OFFICE.

ISAAC B. KLEINERT, OF NEW YORK, N. Y., ASSIGNOR TO THE I. B. KLEINERT RUBBER COMPANY, OF SAME PLACE.

DESIGN FOR SKIRT-FACING.

SPECIFICATION forming part of Design No. 29,084, dated July 19, 1898.

Application filed April 3, 1897. Serial No. 630,660. Term of patent 14 years.

To all whom it may concern:

Be it known that I, ISAAC B. KLEINERT, a citizen of the United States, residing at New York city, in the county of New York and State of New York, have invented and produced a new and original Design for Skirt-Facings, of which the following is a specification, reference being had to the accompanying drawings.

This design relates to a skirt-facing intended to be ornamental as well as useful.

In the accompanying drawings, Figure 1 shows a face view of a skirt-facing, showing my new design. Fig. 2 is a vertical section 15 of the same.

As shown in the drawings, my design consists of a strip of fabric a, on one face of which is a narrower strip b, having a series of small scallops c, projecting downward, as shown.

What I claim as new is—

The design for a skirt-facing herein shown and described.

In testimony whereof I affix my signature, in the presence of two witnesses, this 1st day 25 of April, 1897.

ISAAC B. KLEINERT.
